UNITED STATES PATENT OFFICE.

SOLOMON PLUMMER, OF LOS ANGELES, CALIFORNIA.

DESIGN FOR A SOFT-COLLAR FASTENER.

57,721.

Specification for Design.

Patented Apr. 26, 1921.

Application filed October 11, 1920. Serial No. 416,326. Term of patent 7 years.

To all whom it may concern:

Be it known that I, SOLOMON PLUMMER, a citizen of the United States, residing at Los Angeles, in the county of Los Angeles and State of California, have invented a new, original, and ornamental Design for Soft-Collar Fasteners, of which the following is a specification, reference being had to the accompanying drawing, forming a part thereof.

Figure 1 is a front view of a soft collar fastener showing my new design,
Fig. 2 is a rear view thereof, and
Fig. 3 is a plan view thereof.

I claim:
The ornamental design for a soft collar fastener, as shown.

SOLOMON PLUMMER.
